UNITED STATES PATENT OFFICE.

LOUIS HENRY LLOYD, OF DECATUR, ILLINOIS.

FOUNTAIN-PEN.

No. 928,312.

Specification of Letters Patent.

Patented July 20, 1909.

Application filed December 22, 1908. Serial No. 468,742.

To all whom it may concern:

Be it known that I, LOUIS HENRY LLOYD, a citizen of the United States of America, and a resident of Decatur, in the county of 5 Macon and State of Illinois, have invented certain new and useful Improvements in Fountain-Pens, of which the following is a full and clear specification, reference being had to the accompanying drawings, in 10 which—

Figure 1 is a perspective view of the pen as it appears in use; Fig. 2 is a side elevation with the guard-tube in cross-section, the guard-tube being adjusted to stop the feed 15 and protect the pen; Fig. 3 is a similar view to Fig. 2 on a section through the guard-tube taken at a different angle; and Fig. 4 is a transverse section on the line 4—4 of Fig. 2.

The object of this invention is to provide 20 simple means for entirely stopping the feed when the pen is not in use and also to provide an improved guard-sleeve for protecting the pen while not in use, as more fully herein-after set forth.

Referring to the drawings by reference 25 characters *a* designates an open-ended tube adapted to freely slide on the pen-body and provided with a pin *b* at its upper end which works in a longitudinal guide groove *c* formed 30 in the pen-barrel. At each end this groove is extended laterally to form a reverse curve *c'* whereby the guard-tube may be locked at either end of the pen-barrel. When the 35 guard tube is locked at the upper end of the barrel it is out of the way and when locked at the lower end of the barrel it projects far enough beyond the point of the pen to protect the same.

A small metal collar or band *d* is fastened 40 to the pen-barrel at or near its lower end and made integral with this band is a pair of

spring clamping fingers *e*, *e'*, which extend forwardly one over the top of the pen and the other underneath the feed-tube. These spring arms normally tend to spring away 45 from the pen and the feeder, respectively, but they are so curved that when the guard-tube is slid forwardly into position the inner wall of the tube impinges against both arms and forces them toward each other, causing 50 them to clamp the pen and the feeder tightly but resiliently together and thus prevent leakage of ink while the pen is out of use. The finger *e* which bears against the back of the pen is preferably bifurcated, as shown, to 55 embrace the nibs of the pen and hold them closely together while they are pressed against the feeder.

Having thus fully described my invention, what I claim as new, and desire to secure by 60 Letters Patent, is:

1. A fountain pen provided with a pair of spring clamping fingers extending forwardly from its forward end, and means on the pen-body for clamping said fingers, respectively, 65 against the back of the pen-point and the under side of the feeder.

2. A fountain pen provided with a pair of spring clamping fingers extending forwardly from its forward end, and means on the pen-body for clamping said fingers, respectively, 70 against the back of the pen-point and the under side of the feeder, said means consisting of a guard-tube slidably mounted on the pen-body.

In testimony whereof I hereunto affix my signature in the presence of two witnesses this 12th day of Dec. 1908.

LOUIS HENRY LLOYD.
